UNITED STATES PATENT OFFICE

2,482,036

VENETIAN BLIND ASSEMBLY AND BOTTOM
RAIL THEREFORFrederick L. Stutz, Sturgis, Mich., assignor to
Kirsch Company, Sturgis, Mich., a corporation
of Michigan

Application January 16, 1946, Serial No. 641,506

13 Claims. (Cl. 160—173)

1

This invention relates to improvements in Venetian blind assembly and bottom rail therefor.

The main objects of this invention are:

First, to provide an improved bottom rail for Venetian blinds which may be economically produced and includes means for effective guiding of pull cords to and within the bottom rail and minimizes the wear thereon.

Second, to provide a Venetian blind assembly including ladder tapes and pull cord and bottom rail in which the ladder tapes and pull cords are effectively associated with the bottom rail, the bottom rail being provided with non-metallic pull cord guide members.

Third, to provide a structure having these advantages which is attractive in appearance and comparatively light in weight.

Objects relating to details and economies of the invention will appear from the description to follow. The invention is defined and pointed out in the claims.

A preferred embodiment of the invention is illustrated in the accompanying drawing, in which:

Fig. 1 is a front elevation of a Venetian blind embodying the invention in partially collapsed position, parts being shown conventionally.

Fig. 2 is an enlarged fragmentary view of the bottom bar in section on a line corresponding to line 2—2 of Fig. 5.

Fig. 3 is a fragmentary view mainly in longitudinal section on a line corresponding to line 3—3 of Fig. 2.

Fig. 4 is a fragmentary bottom view of the bottom bar with the ladder tape and cord guide member retaining clip removed.

Fig. 5 is a fragmentary view mainly in section on a line corresponding to lines 5—5 of Figs. 2 and 3.

Fig. 6 is a bottom perspective view of one of the pull cord guide members.

In the embodiment of the invention illustrated, 1 represents the head bar, 2, 2 the pull cords which in this embodiment constitute a single cord, the guide pulleys for the pull cords within the head bar not being illustrated. The ladder tapes 3 are of well known type and designed to support the slats 4 which are conventionally illustrated.

The bottom bar designated generally by the numeral 5 is of horizontal flattened cross section, being formed of sheet metal rolled upon itself, the edges of the sheet metal being indicated at 6 in one edge of the bottom bar, desirably the

2

inner edge so that the outer edge and top and bottom present jointless surfaces.

The top wall 7 of the bottom bar is provided with horizontally spaced elongated slots 8 extending transversely of the bottom bar. The bottom wall 9 of the bottom bar is provided with holes 10 in opposed relation to the slots 8 and aligned therewith, these holes being round, in the structure illustrated.

10 The pull cord guide members 11 are, in the preferred embodiment illustrated, formed of molded plastic material and have elongated holes 12 therein, there being flanges 13 on the upper end of the guide members which fit into the slots 8 in the top of the bottom bar engaging the side edges of the slots thereby preventing rotative movement of the guide members in the bottom bar.

15 The holes 10 in the bottom of the bottom bar are of such size as to permit the introduction of the guide members therethrough with the lower ends of the guide members projecting into the holes. This further supports the guide members against transverse or longitudinal movement in the bottom bar.

20 The guide members as illustrated have downwardly converging sides 14 with recesses 15 therein through which the cords may be extended. The edges of the recesses 15 merge into 25 the holes 8 with curved surfaces as shown at 16.

20 The lower ends of the ladder tapes are desirably folded as shown at 17, these folds being stitched as indicated at 18. The ladder tapes overlap the lower ends of the guide members so that the ladder tape retaining clips 19 serve the 35 double function of retaining the guide members and securing the ladder tapes. These clips are provided with spring fingers 20 which engage the edges of the bottom bar.

40 To prevent longitudinal movement of the clips, they are provided with lugs or tongues 21 which engage the slots 22 provided at opposite sides of the openings 10 so that when the clips are engaged they cannot shift longitudinally of the 45 bottom bar. These clips and the manner of their engagement with the ladder tapes with the exception of these lugs are substantially the structure shown in the Grassby Jr. Patent 2,079,852 issued May 11, 1937. However, in that case the 50 clips have no relation to the pull cord securing means.

With the parts thus arranged, the pull cord is rove through the guide members as is shown in the drawings and is effectively guided and attached to the bottom bar with a minimum of

wear on the cord resulting from repeated manipulation of the pull cord.

The structure is economical in its parts and in their assembly and is highly attractive in appearance and is easily kept clean which characteristic, it will be appreciated, is highly desirable in Venetian blinds.

I have not attempted to illustrate or describe the various adaptations such as modifications in shape which might be desirable to meet different cases or conditions as it is believed that this disclosure will enable those skilled in the art to embody or adapt the invention as may be desired.

Having thus described my invention, what I claim as new and desire to secure by Letters Patent, is:

1. In a Venetian blind, the combination of a horizontally flattened tubular bottom bar having longitudinally spaced transverse slots in the top wall thereof and openings in the bottom wall thereof opposed to said slots, pull cord guide members of molded plastic having elongated holes therethrough registering with said slots in said top wall and having top flanges engaging the side edges of the slots in the top wall, said guide members having downwardly converging side walls with recesses therein opening to said holes thereof, the inner edges of the recesses being curved to merge into said holes, the guide members being introducible through the openings in the bottom wall of the bar, the guide members having curved end portions extending into said bottom openings, ladder tapes, a pull cord rove through adjacent guide members, the lower ends of the ladder tapes being wrapped around the edges of the bottom bar to overlie the bottom thereof, and clips having opposed pairs of spring fingers retainingly engaging the edges of the bottom bar and the tape ends therearound, the lower clip engaged ends of said ladder tapes overlapping the lower ends of said guide members whereby the guide members are retained by said clips, the bottom bar having slots at each side of said bottom openings, said clips having lugs engaging said slots.

2. In a Venetian blind, the combination of a horizontally flattened tubular bottom bar having longitudinally spaced transverse slots in the top wall thereof and openings in the bottom wall thereof opposed to said slots, pull cord guide members of molded plastic having elongated holes therethrough registering with said slots in said top wall and engaging the side edges of the slots in the top wall, said guide members having recesses therein opening to said holes thereof, the guide members being introducible through the openings in the bottom wall of the bar, ladder tapes, a pull cord rove through adjacent guide members, the lower ends of the ladder tapes being wrapped around the edges of the bottom bar to overlie the bottom thereof, and clips springably engaging the edges of the bottom bar and the tape ends therearound, the lower clip engaged ends of said ladder tapes overlapping the lower ends of said guide members whereby the guide members are retained by said clips.

3. In a Venetian blind, the combination with ladder tapes and a pull cord, of a horizontally flattened tubular bottom bar having spaced holes in the top wall thereof and openings in the bottom wall thereof opposed to said holes, pull cord guide members having holes therein registering with said holes in said top wall and having top flanges engaging the edges of the holes in the top wall, said guide members having side recesses therein opening to said holes thereof, the guide members

being introducible through the opening in the bottom wall with the guide members extending into said bottom openings, the pull cord being rove through adjacent guide members, the lower ends of the ladder tapes being wrapped around the edges of the bottom bar to overlie the bottom thereof, and clips having spring members retainingly engaging the bottom bar and the tape ends therearound, said clips retainingly engaging the lower ends of said guide members whereby the guide members are retained by said clips.

4. In a Venetian blind, the combination with ladder tapes and a pull cord, of a horizontally flattened tubular bottom bar having spaced holes in the top wall thereof and openings in the bottom wall thereof opposed to said holes, pull cord guide members having holes therein registering with said holes in said top wall and having top flanges engaging the edges of the holes in the top wall, said guide members having side recesses therein opening to said holes thereof, the guide members being introducible through the opening in the bottom wall with the guide members extending into said bottom openings, the pull cord being rove through adjacent guide members; and means for retaining said guide members in the bottom bar.

5. In a Venetian blind, the combination of a tubular bottom bar having holes in the top thereof and openings in the bottom thereof aligned with said top holes, pull cord guide members having apertures therethrough registering with said top holes and having portions extending into the said top holes and having side openings communicating with said apertures, the guide members being introducible through the bottom openings with portions thereof extending into said bottom openings, a pull cord rove through adjacent guide members, and means supportingly engaging the lower ends of said guide members.

6. A horizontally flattened tubular bottom bar for Venetian blinds having a transverse slot in the top wall thereof and an opening in the bottom wall thereof opposed to said slot, a pull cord guide member of molded plastic having an elongated hole therein registering with said slot in said top wall and having top flanges engaging the edge of the slot in the top wall, said guide member having a side recess therein opening to said hole thereof, the guide member being introducible through the opening in the bottom wall with the guide member extending into said bottom opening, and a ladder tape attaching clip having spring fingers retainingly engaging the edges of the bottom bar, said clip also constituting means for retaining said guide member within said bar.

7. A tubular bottom bar for Venetian blinds having a top hole and an opposed bottom opening, a pull cord guide member having an aperture therein registering with said hole in the top of the bottom bar and engaging the edge of said hole, said guide member having a pull cord receiving side opening therein opening to said aperture thereof, the guide member being introducible through the opening in the bottom wall with the guide member extending into the bottom opening, and means for retaining said guide member.

8. A tubular bottom bar for Venetian blinds having a top hole and an opposed bottom opening, a pull cord guide member having an aperture therein registering with said hole in the top of the bottom bar, said guide member having a pull cord side opening therein opening to said aperture thereof, the guide member being introducible through the opening in the bottom wall,

and a ladder attaching member detachably engaged with said bar and constituting a retaining means for said guide member.

9. A tubular bottom bar for Venetian blinds having a top hole and an opposed bottom opening, a pull cord guide member having an aperture therein registering with said hole in the top of the bottom bar, said guide member having a pull cord side opening therein opening to said aperture thereof, the guide members being introducible through the opening in the bottom wall, and means for retaining said guide member in position within said bar.

10. A tubular bottom bar for Venetian blinds having a transversely elongated hole in the top thereof and an opposed opening in the bottom thereof, a pull cord guide member having an elongated pull cord aperture therein registering with said hole in the top of said bottom bar and having parts thereof engaging the side edges of such hole, the guide member having a side opening therein opening to the said pull cord aperture thereof, the guide members being introducible through the opening in the bottom of said bottom bar, and a ladder tape attaching means constituting retaining means for the guide member.

11. A tubular bottom bar for Venetian blinds having a transversely elongated hole in the top thereof and an opposed opening in the bottom thereof, a pull cord guide member having an elongated pull cord aperture therein registering with said hole in the top of said bottom bar and having parts thereof engaging the side edges of such hole, the guide member having a side opening therein opening to the said pull cord aperture thereof, the guide members being introducible through the opening in the bottom of

said bottom bar, and means for retaining said guide member within said bar.

12. A tubular bottom bar for Venetian blinds having a hole in the top thereof and an opposed opening in the bottom thereof, a pull cord guide member of molded material having a pull cord aperture therein registering with said hole in the top of said bottom bar, the guide member having a side opening therein opening to the said pull cord aperture thereof, the guide members being introducible through the opening in the bottom of said bottom bar with the guide member projecting into the bottom opening, and a ladder tape attaching means constituting retaining means for the guide member.

13. A tubular bottom bar for Venetian blinds having a hole in the top thereof and an opposed opening in the bottom thereof, a pull cord guide member having a pull cord aperture therein registering with said hole in the top of said bottom bar, the guide member having a side opening therein opening to the said pull cord aperture thereof, the guide members being introducible through the opening in the bottom of said bottom bar with the guide member projecting into the bottom opening, and means for retaining said guide member.
